ANCHOR

John K. Northrop, Los Angeles, Calif.

Application August 20, 1940, Serial No. 353,352

11 Claims. (Cl. 114—208)

My invention relates to anchors, and more particularly to an anchor which is adapted to enter penetrable bottom substantially independently of the weight of the anchor.

Among the objects of my invention are, to provide a lightweight anchor capable of penetration in bottom, due to the planing characteristics of the fluke; to provide an anchor of light weight, having a high molding power; to provide a single fluke anchor of the swinging fluke type which will not rotate out of bottom during, or after penetration into the bottom; to provide an anchor having a holding power substantially independent of anchor weight, having both a planing fluke, and a planing stock; to provide a single fluke type anchor having a holding power substantially independent of weight; to provide a means and method of preventing a single fluke anchor from rotating during and after penetration into the bottom.

In Patent No. 2,075,827, issued April 6, 1937, to myself and Harry M. Gesner, we have described and claimed an anchor penetrating bottom and holding therein substantially independently of the weight of the anchor, because of the angular relationships of the fluke to bottom when the anchor first rests on bottom, during penetration, and after full engagement with the bottom. The prior anchor, however, had a fluke fixed with relation to the shank and the present invention is directed toward an anchor having similar planing characteristics in penetrable bottom with, however, a structure embodying a single pivoted fluke, together with means to assure proper penetration in the bottom without rotation.

Anchors of the single fluke type have a tendency, during penetration and thereafter, to rotate, and in many cases such a rotation will occur in spite of the use of a stock, particularly if the stock is of such section as to aid in the progression of the anchor into bottom. This rotation may be of such magnitude that the anchor fluke will completely emerge from the bottom, and thereby destroy the holding power of the anchor. The present invention provides means for preventing rotation of the anchor, even though a planing type stock is used.

In all anchors of the type where penetration is substantially independent of weight, it is highly desirable that the shank of the anchor be of such section that it may readily progress downward into penetrable bottom in order that the anchor may become deeply embedded. For a like reason, it is desirable that the stock of the anchor be of such section that it offers relatively little

resistance to forward movement of the anchor and it is also desirable that this stock either offer minimum resistance to downward motion of the anchor in bottom, or actually aid in the downward motion. The contour of a stock, however, which offers little resistance to forward and downward motion of the anchor in bottom is not the contour favorable to proper stock action, i. e., the prevention of anchor rotation during and after embedding of the anchor.

I have found, however, that if, in an anchor planing into bottom substantially independent of weight, the ends of the stock only are provided with a drag member, the overall resistance of the stock to forward and downward motion is relatively small, whereas the drag exerted at the ends of the stock by these drag members is sufficient to prevent the fluke from rotating out of bottom.

20 My invention may be more readily understood by direct reference to the drawing wherein:

Fig. 1 is the side view of a form of my invention embodying a swinging fluke having angular relationships to the shank giving the anchor the ability to penetrate the bottom substantially independent of weight.

Fig. 2 is a top view of the anchor shown in Fig. 1, with the fluke centralized.

Fig. 3 is a top view of an anchor having a modified drag member on the ends of the stock.

Fig. 4 is a fragmentary side view showing the drag member used on the anchor of Fig. 3.

Referring to Figs. 1 and 2, a shank 1 is formed of spaced frame members 2 and 3, these frame members converging at one end thereof to a junction 4, this junction being provided with a cable ring 5, to which the anchor cable may be attached leading to a vessel or aircraft. Before convergence, the frame members 2 and 3 are parallel and their opposite extremities are provided with pivot bolts 6 to which fluke arms 7 are hinged. Fluke arms 7 extend both front and rear of pivot bolts 6, the front portion of each arm being longer than the rear portion thereof.

45 Joining the longer portions of fluke arms 7 is a planar fluke 8, of thin section and extended area, the arm joints 9 being preferably welded. Fluke 8 is provided with a pointed bottom penetrating end 10, and this pointed end is protected with a penetration tip 11 applied thereto. The edges of end 10 are preferably sharpened.

The opposite ends of the fluke arms 7 on the other side of pivot bolts 6 are joined by a planar stock 12 passing through each arm, this stock 55 being held in position by stock pins 13. Stock

12 extends laterally beyond fluke arms 7, preferably equidistant on both sides thereof. I prefer to make stock 12 of sheet material of substantially the same gauge and weight as fluke 8 and mount stock 12 in the same plane as fluke 8. Stock 12 is also preferably provided with a sharpened edge 14 to assist penetration.

The outer ends of stock 12 are provided with drag members 15, in this case being bulbous members solidly riveted or otherwise attached to the ends only of stock 12 on both upper and lower surfaces. Such members provide an increased drag only at the outer ends of the stock. I have found that such increased drag, even though small compared to the drag of a stock having an entire contour similar to that of the drag members is sufficient to prevent rotation during penetration, as will be explained later.

The swing of fluke arms 7 and attached fluke 8 with relation to shank 1 is controlled by fluke arm brackets 16 applied to fluke arms 7, these brackets being provided with laterally extending portions 17 engaging shank members 2 and 3 after the fluke arms have assumed a predetermined angle with shank 1.

As set forth in Patent No. 2,075,827, issued April 6, 1937, to myself and Harry M. Gesner, the fluke angle just before, during, and after penetration, is very important to insure proper penetration and holding power thereafter of a light weight anchor, such holding power of course, being increased by complete bottom penetration of the anchor, including penetration of the shank and in many cases of the stock. It is always desirable to have the forward pull of the anchor cable tend to embed the anchor more and more under the cable pull instead of dragging the anchor directly forward. I have found that when a fluke of thin section and relatively large area, with the fluke arms, and fluke length so proportioned to the length of the shank that the center of area of the fluke when registering with the bottom during penetration thereof, assumes a planing angle of substantially 45° to bottom, that maximum planing ability for bottom penetration substantially independent of weight is developed. I have also found that good initial penetration of the fluke occurs when the fluke is presented to the bottom with the plane of the fluke making an angle to the bottom plane of not substantially over 60°, and preferably between 50° and 60°. I have also found that the fluke will hold with maximum holding power when fully embedded when the fluke plane is held to an angle with the shank plane within a range of from 25° to 35°, a preferred angle being 26°. I have found, however, that it is possible to vary both the preferred initial angle of 60° and the preferred final angle of 26° somewhat if the planing angle of substantially 45° is maintained when the center of area of the fluke registers with the bottom plane. The approximate center of area of a fluke of a particular shape is easily determined by inspection, and the actual center of area is easily calculated.

In the modification shown in Figs. 3 and 4, a drag member comprising a disc 20 is attached to each end of the stock by a flexible link, preferably a chain 21, otherwise the anchor is the same as the modification formerly described. Other fixed or flexibly attached drag members will, of course, suggest themselves to those skilled in the art, and I do not wish to be limited to any particular type or shape or mode of attachment of the drag members to the stock

ends, the main object being the provision of a member increasing the drag of the stock only adjacent the ends thereof.

In operation the anchor is, of course attached to its cable and thrown overboard from the vessel or craft it is desired to anchor. Upon reaching bottom, the shank thereof will, due to its shape, tend to lie flat on the bottom. Two fluke conditions may occur. Either the ends 17 of brackets 16 will penetrate the bottom and allow the fluke to lie generally flat on the bottom or, if the ends 17 cannot enter fully, they will rotate the fluke upwardly. However, in either case the first forward movement of the anchor causes the drag on the ends 17 to rotate the fluke so that the point thereof is presented to bottom at an angle which causes it to start penetration and engagement with the bottom. The fluke then continues to penetrate and rotate until the final angle to the shank is reached, as determined by the restrictive engagement of ends 17 with the shank members.

The point of the fluke therefore, under the forward pull catches in bottom and the anchor 25 jack-knifes on pivot 6 until the anchor rests on the bottom at three points, cable attachment 5, fluke point 11, and one of the drag members 15 on stock 12. It is to be noted that so far as the drag efficiency of the stock is concerned, the 30 drag exerted by the stock in this position is fully equivalent to any drag that would be exerted by a stock having an overall section similar to the section of drag member 15. Continued forward pull then progresses the fluke into bottom with 35 its maximum angle to the shank as determined by bracket 16. Any tendency for the fluke to rotate is counteracted by the drag of the drag members. When the fluke has penetrated bottom until the center of area of the fluke registers 40 with the bottom plane, the fluke assumes a 45° angle thereto and maximum planing action occurs. The anchor then rapidly progresses into the ground under the cable pull. As the spaced shank members reach bottom they penetrate 45 the ground readily because they present their narrowest section to the bottom. As the stock approaches the bottom plane and enters it, the stock itself also planes into the ground, as it is in coplanar relationship to the fluke.

50 As the anchor embeds itself, the drag members 15 offer relatively much smaller resistance to forward and downward progression than if the entire stock had the same section. If, after embedding in the bottom there is any tendency for the anchor to rotate, one of the embedded members may emerge from the bottom plane leaving only the other drag member in the bottom. This unbalance of drag will then tend to stop further rotation and to straighten out the anchor.

60 In the device shown in Figs. 3 and 4, the drag members are flexibly attached to the ends of the stock by chain 21 and in this case the stock may be embedded well below the bottom plane with the drag members above the bottom plane.

65 Any rotational tendency of the anchor will then cause one of the drag members to engage the bottom with the other drag member lying on top of the bottom. In this case the drag, being wholly on one side of the stock, will straighten out the 70 rotation. If, however, the anchor has been embedded to such an extent in the bottom that both of the flexibly attached drag members 20 are embedded therein, then it will be apparent that due to the forward and downward progression of the anchor, the drag members will be

above the stock level. Under these conditions, the first tendency of the stock to rotate will continue the drag on one member, whereas any upward movement of the stock on the opposite side will tend to take the strain off the attached drag member, thus unbalancing the drag and straightening out the anchor. The loose attachment of the drag members therefore allows embedding of the complete anchor without the embedding of the drag members. Thus the drag members do not oppose complete submergence of the anchor in bottom, yet are always ready to combat rotation.

It will, therefore, be clear that I have provided an anchor having a pivoted fluke operating within a shank frame which will penetrate independently of weight and which has completely solved the problem of single fluke anchors of the Navy type operating within a frame, i. e., the problem of rotation, and that I have solved this problem by providing lumped drag stresses at the outer ends of the stock in such a position with relation to the anchor that the drag becomes unbalanced the moment any rotation of the anchor occurs, this unbalance immediately tending to stop the rotation.

I claim:

1. An anchor comprising a pair of spaced frame bars forming a shank and converging toward each other at one end thereof to form a junction, a cable attachment at said junction, a pair of spaced fluke bars each pivoted adjacent the other end of a frame bar to swing inside of and adjacent said frame bars and extending on both sides of said pivot, means for limiting the swing angle of said fluke bars relative to said frame bars, a substantially planar thin section fluke joining end portions of said fluke bars, a substantially planar thin section stock bar joining and extending laterally in substantially the plane of said fluke beyond the opposite end portions of said fluke bars on the other side of said pivot, and drag members attached to the outer ends of said stock-bar spaced from said frame bars and shaped to materially increase the effective resistance of said stock-bar ends to penetration of ground.

2. In an anchor comprising a shank, a fluke attached adjacent one end of said shank, a stock extending laterally adjacent the attachment of said fluke to said shank, and a pair of freely depending drag members one flexibly attached to each end of said stock.

3. In an anchor comprising a shank, a fluke attached adjacent one end of said shank, a stock extending laterally adjacent the attachment of said fluke to said shank, and a pair of freely depending drag members one attached to each end of said stock by a flexible link.

4. In an anchor comprising a shank, a fluke attached adjacent one end of said shank, a stock extending laterally adjacent the attachment of said fluke to said shank, and a pair of freely depending drag members one attached to each end of said stock by a chain.

5. An anchor having a shank member, a fluke arm member pivoted adjacent one end of said shank member and extending in both directions from said pivot, a substantially planar thin section fluke attached to said fluke arm member

on one side of said pivot, and a laterally extending planar stock attached to said fluke arm on the opposite side of said pivot, said stock and said fluke being substantially coplanar in all positions of said fluke and stock.

6. An anchor having a shank member, a fluke arm member pivoted adjacent one end of said shank member and extending in both directions from said pivot, a substantially planar thin section fluke attached to said fluke arm on one side of said pivot, and a laterally extending planar stock attached to said fluke arm on the opposite side of said pivot, said stock and said fluke being substantially coplanar and of substantially the same thickness.

7. An anchor having a shank member, a fluke arm member pivoted adjacent one end of said shank member and extending in both directions from said pivot, a substantially planar thin section fluke attached to said fluke arm member on one side of said pivot, and a laterally extending thin section planar stock attached to said fluke arm on the opposite side of said pivot, said stock and said fluke being substantially coplanar, and a drag member on each end of said stock.

8. An anchor having a shank member, a fluke arm member pivoted adjacent one end of said shank member and extending in both directions from said pivot, a substantially planar thin section fluke attached to said fluke arm member on one side of said pivot, and a laterally extending planar stock attached to said fluke arm on the opposite side of said pivot, said stock and said fluke being substantially coplanar, a freely depending drag member flexibly attached to each end of said stock.

9. Apparatus in accordance with claim 1 wherein said drag members are flexibly attached to the ends of said stock-bars.

10. An anchor adapted to penetrate in bottom substantially independent of weight, having a shank, a cable attachment at one end of said shank, a holding and planing member pivoted adjacent the other end of said shank, said member having thin substantially coplanar planing portions of substantially the same thickness on each side of the axis of rotation of said member, one of said portions extending radially from said pivot to act as a fluke, the other portion being extended in an axial direction relative to said pivot to act as a stock.

11. An anchor adapted to penetrate in bottom substantially independent of weight having a shank, a cable attachment at one end of said shank, a holding and planing member pivoted adjacent the other end of said shank, said member having thin substantially coplanar planing portions of substantially the same thickness on each side of the axis of rotation of said member, one of said portions extending radially from said pivot to act as a fluke, the other portion being extended in an axial direction relative to said pivot to act as a stock and drag members attached to the outer ends of said portion acting as a stock, said drag members being spaced from said shank and shaped to materially increase the cross-sectional area of said ends at a right angle to the plane of said member.
